(57) **CLAIM**

The ornamental design for a display screen or portion thereof with graphical user interface, as shown and described.

DESCRIPTION

The FIGURE is a front view of a display screen or portion thereof with graphical user interface showing my new design.

The peripheral broken lines depict a display screen or portion thereof and form no part of the claimed design. The vertical lines in the line graph form part of the claimed design. All other broken lines and stippling show portions of the graphical user interface and form no part of the claimed design.
